UNITED STATES PATENT OFFICE

2,658,207

BABY CRIB MATTRESS ELEVATOR

Jesse J. Robbins, Glendale, Calif., assignor to
 Stylofede Corporation, a corporation of California

Application January 4, 1950, Serial No. 136,762

9 Claims. (Cl. 5—11)

1

The invention relates to mechanisms used in a baby crib or the like for adjusting the height of the mattress frame, and more particularly to such mechanisms as may be operated by manual cranking to raise and lower the mattress frame as may be desired.

Mechanisms of the character described heretofore available have been relatively complicated and costly in their construction and installation, usually requiring pawl and ratchet types of devices, springs, and the like, connected by a flexible cable to the mattress frame, and which are subject to getting out of order, overrunning and piling up of the cable, and sometimes complete jamming of the mechanism. Since such devices are customarily built into the interior body frame of the crib, repair or replacement of parts or disentangling of the cable is a major and difficult operation.

An object of the present invention is to provide a device of the character described made up of a unitary assembly of parts and which may be quickly and easily secured in place in the headboard of a crib and simply connected by cables to the mattress frame, and wherein the design and construction of the parts is such that the mechanism will be completely foolproof and safe in its operation, and positively avoid the tendencies of former devices in the piling up and entanglement of cable and jamming and breakage of the mechanism.

Another object of the invention is to provide a mechanism of the character above which is essentially effortless and smooth in its operation and will safely and securely hold the mattress frame at any desired position over the full range of movement provided for the mattress frame.

A further object of the invention is to provide a mechanism of the character described in which the design and sturdiness of the several parts making up the mechanism permits a complete enclosure of the mechanism within the frame of the crib without exposure of projecting or moving parts which may constitute a safety hazard for the crib occupant and others, and in which the expected life of the mechanism is at least as long as that of the crib, so that no dismantling of the crib need be contemplated to effect repair or replacement throughout the normal life expectancy of the crib.

The invention possesses other objects and features of advantage, some of which, with the foregoing, will be set forth in the following description of the preferred form of the invention which is illustrated in the drawings accompany-

2

ing and forming part of the specification. It is to be understood, however, that variations in the showing made by the said drawings and description may be adopted within the scope of the invention as set forth in the claims.

Referring to said drawings:

Figure 1 is a perspective view of a baby crib having incorporated therein a mechanism constructed in accordance with the present invention and having a portion of the rear corner post broken away to more fully disclose the construction thereof.

Figure 2 is a horizontal section through the crib headboard taken on the plane of line 2—2 of Figure 1.

Figure 3 is a vertical section through the crib headboard taken substantially on the plane of line 3—3 of Figure 2.

Figure 4 is a fragmentary vertical cross-sectional view of the headboard showing the mechanism of the present invention in side elevation.

Figure 5 is a horizontal section taken substantially on the plane of line 5—5 of Figure 4.

Figure 6 is a vertical cross-sectional view of the mechanism illustrated in Figure 4 and is taken substantially on the plane of line 6—6 of Figure 4.

Figure 7 is a vertical sectional view of the mechanism illustrated in Figure 4 and is taken substantially on the plane of line 7—7 of Figure 4.

Figure 8 is a side elevation of a crib headboard and corner post with portions thereof broken away and shown in cross section to disclose in side elevation a modified form of the construction of my invention.

Figure 9 is a cross-sectional view of the headboard illustrated in Figure 8 on an enlarged scale and is taken substantially on the plane of line 9—9 of Figure 8 with a portion of the mechanism broken away and shown in cross section.

The mechanism of the present invention and as illustrated in the accompanying drawings is adapted for mounting within the headboard 11 of a baby crib generally denoted by numeral 12 in Figure 1 and is operatively connected by a flexible cable 13 to the mattress frame 14 of the crib. Preferably, the mattress frame is provided with corner brackets 16 which are mounted for vertical reciprocation within slots 17 provided in the corner posts 18 of the crib frame. In the form of the invention illustrated in Figures 1 through 7, the headboard 11 is provided with an internal groove or channel 19 which extends over the full length of the headboard and

registers at its outer ends with vertical openings 21 provided in the corner posts 18 and which openings, in turn, register with the slots 17. Sheaves 22 may be provided in the headboard 11 at the joinder of the guideways 19 and 21 for supporting the cable 13. A similar arrangement of guideways 23 and sheaves 24 is provided in lower frame sides 26 of the crib whereby the cable 13 may be extended across the headboard 11 down the corner posts 18 at the head of the bed, where connection may be effected to the brackets 16 thereat, and then carried around the sheaves 24 at the lower joinder of the corner posts and frame sides 26 at the head of the bed, along the guideways 28 to the corner posts 18 at the foot of the bed, thence around sheaves 24 up the slots 17 provided in such corner posts and over sheaves 27 mounted internally within such slots adjacent the upper ends thereof, and back down to the brackets 16 mounted in the corner post slots 17 at the foot of the bed. In this manner, a foreshortening of the cable at the headboard 11 of the crib will cause a relative raising of the frame 14 while a paying-out of the cable will permit a lowering of the frame, the latter movement being effected in the present construction by the weight and gravitation of the frame without need of assisting springs.

As illustrated in the accompanying drawings, the mechanism of the present invention consists, briefly, of a rotary drive means provided in the headboard of the crib and operatively connected to the cable and effecting upon rotation in one direction a reeling-in of the cable and a raising of the mattress frame and, conversely, on rotation in an opposite direction, a paying-out of the cable and lowering of the mattress frame. Rotation of the drive means is here conveniently effected by a manually engageable crank 28. Incorporated in the drive assembly is a stop means functioning to limit the rotation of the drive and paying-out of the cable to a desired lowermost positioning of the mattress frame, and co-operating therewith is means automatically functioning to disengage the crank 28 from its drive connection when the stop means is effective in limiting further rotation. In this manner, a jamming of the mechanism or overrunning and piling up of the cables, frequently encountered in prior-art devices, is positively prevented, as is also a manual forcing of the mechanism beyond its stopped position, which has heretofore been a cause of stripping or otherwise breaking internal parts of the mechanism.

The mechanism as above described is composed of a unitary assembly of co-acting parts which may be quickly and easily dropped into place and fastened in the headboard 11 of the crib formed for receipt of the mechanism. The several parts are assembled in a bracket 29 which may be conveniently secured to the headboard by screws 30, ears 25 being formed on the bracket as shown to accommodate certain of the screws. When viewed as disposed in Figure 4, the bracket is provided with spaced parallel upper and lower sides 31 and 32, and serves to support for rotation therebetween a cable drum 33, the latter being journaled for rotation about a vertical axis and having a diametrically extending opening 34 for receipt of the cable 13. Rotation of the drum 33 is preferably effected by gear means including a spur gear 36 here desirably in the form of a worm pinion, and connected for joint rotation with the drum by means of an axial shaft 37. As will be best seen in Figure 7, the

gear 36 is formed with an axially extending cylindrical hub 38 which is journaled for rotation in a bearing opening 39 provided in the side 31 of the bracket 29. The aforementioned stop means is here embodied in the form of a hollow nut 41 threaded into an opening 42 provided in the opposite bracket side 32 in axial alignment with the hub bearing opening 39. Preferably, the gear and its hub, the drum 33, and the nut 41 are provided with axial bores 43, 44 and 46 respectively for receipt of the shaft 37 and joint rotation of these parts may be conveniently effected by the provision of a non-circular inter-fit therebetween. To accomplish this, the shaft 37 may be formed of rectangular cross section as shown in Figures 5 and 7, and the bores 43, 44 and 46 broached to provide a rectangular cross section interlocking with the shaft. Relative longitudinal displacement of the shaft 37 within the bores 43, 44 and 46 is here prevented by extending the cable 13 through a transverse opening 47 provided in the shaft in alignment with drum opening 34, the cable in this manner serving as an interlocking key to prevent such displacement.

Preferably, the drum 33 is formed with an end recess 48 for accommodating and housing the nut 41, permitting axial reciprocation of the nut upon joint rotation of the drum and nut. Preferably also, the threaded connection between the nut 41 and the bracket side 32 is such that the nut will screw in an outward direction from the recess 48 and side 32 upon rotation of the drum in a direction paying-out the cable. As will be seen from Figure 7, the nut 41 is provided with an enlarged head 49 arranged to engage the inside face of bracket side 32 to provide a stop for the further screwing of the nut in an outward direction, thereby preventing further rotation of the shaft 37 and the drum 33 interlocked with the nut. The mechanism also provides a stop for its opposite terminal position, corresponding to a fully-raised position of the mattress frame, by reason of the depth of the recess 48 limiting the inward movement of the nut 41. As here shown, the recess 48 is extended inwardly in the drum to the cable opening 34 so that the inward movement of the nut is determined by the engagement of the nut head 49 with the cable. The length of the nut should roughly correspond to the full depth of the recess with the cable removed, thereby permitting in assembly the insertion of the drum in the space provided between the gear 36 and the bracket side 32. After insertion of the drum and threading of nut 41 into opening 42 to clear the diametric opening 34, the cable may be inserted through the drum opening 34 and around the various sheaves of the crib frame as above described, and anchored to the mattress frame brackets 16 at a position corresponding to the desired lowermost location of the frame. Since a straight-through opening is provided in the drum 33, an initial threading of the cable as above described is facilitated in that an equalized and uniform tension may be placed on the cable without interference of the interposed drum. Also, since no direct anchoring of the cable to the drum is effected, the strain on the cable is automatically self-adjusting throughout the entire life of the unit, and is permitted to equalize on opposite sides of the drum whenever the mattress frame is lowered to its lowermost desired position.

Rotation of the gear and drum assembly as

above described is preferably effected by a worm gear 51 connected to crank 28 and mounted for rotation between the opposed front and rear sides 52 and 53 of the bracket, with the worm gear enmeshed with worm pinion 36. The use of a worm gear is highly desirable for obtaining smooth and effortless rotation of the drum and also for providing a positive holding of the drum against rotation under the weight of the mattress frame, mattress, and crib occupant, without the use of any ratchet or other catch or holding means, the worm and pinion gears inherently and in themselves providing such a locking of the drum except when the drum is rotated by means of the crank 28. In this manner, the mattress frame may be elevated or lowered to any desired position over its full range of movement and the frame will be automatically immovably held in such position, to the entire safety of the crib occupant. This holding of the mattress frame is completely unaffected by jumping or bouncing of the baby within the crib, and is accomplished without any undue strain on the mechanism or likelihood of breaking of any parts or impairment of the operation thereof.

As will be best seen in Figures 5 and 6, the worm gear 51 is supported by a shaft 54 mounted through an axial bore 56 in the gear and having cylindrical end portions 57 and 58 journaled for rotation in aligned openings 59 and 61 in the bracket sides 52 and 53. The section of the shaft 54 extending through the worm may be of rectangular or other non-circular cross section, and the bore of the worm gear is preferably broached to provide an inter-fitting cross section to lock the shaft and gear for joint rotation. Longitudinal displacement of the shaft with respect to the bearing openings 59 and 61 may be conveniently prevented as here shown by means of a set screw 62 threaded through the wall of the bracket side 52 and engaged in a peripheral recess 63 in the shaft end 57.

As hereinabove noted and as an important feature of the present invention, a detachable connection is provided between the crank 28 and the worm gear so that upon rotation of the drive means to the lowermost position of the mattress frame, where further movement is stopped by nut 41, an automatic disengagement of the crank from the drive means is effected to prevent a forcing of the parts. A preferred form of such automatic release is provided in the present construction by threadably attaching the crank to the worm gear so that upon rotation of the drive to the stop as aforesaid further rotation of the crank will effect an unwinding of the threaded connection and a de-coupling of the crank from the worm gear. This construction is best seen in Figure 5, where the crank end 64 is secured to a nut 66 threaded into the end 57 of the worm shaft, the threaded connection being such that the nut 66 is threaded home upon rotation of the crank in a direction reeling in the cable. Upon rotation of the crank in such direction, an enlarged head 67 on the nut is screwed into abutment with the end face 68 of the worm shaft, when further relative rotation between the nut and the shaft is prevented, and the crank, nut and shaft thereby locked for joint rotation. The frictional grip of the threaded portions will hold the parts in engagement on rotation of the crank in an opposite direction, that is, one paying out the cable from the drums, until the drum is rotated to its end position as determined by stop nut 41, when further rotative effort applied to the crank 75

will merely unscrew the nut 66 from the shaft end 57, thereby de-coupling the drive.

Preferably, the crank end 64 is detachably secured to the nut 67 so as to permit the quick and ready removal of the crank from the mechanism when desired. As here shown, the crank end 64 is inserted within a bore or recess 69 provided in the nut 66 and is releasably retained therein by a spring snap ring 71 carried in a recess in the bore and engageable in a peripheral groove 72 in the crank end 64, to hold the crank end and nut for joint rotation. The inner terminal end 73 of the crank is here shown of reduced and non-circular cross section adapted to fit a similarly shaped socket at the inner end of recess 69.

A modified form of the invention is illustrated in Figures 8 and 9 wherein the rotary drive means mounted in the headboard 11a of the crib includes an elongated drive shaft 74 which extends over substantially the full length of the headboard and into overlying relation to the openings 21a in the corner posts 18a of the crib. In this manner, drums 76 and 77 may be carried for rotation at the outer ends of shaft 74 for connection to cables 13a, without requiring the extension of the cables through the length of the headboard of the crib.

In this form of the invention, the mechanism is again unitarily assembled in a bracket 29a having lugs 25a and screws 30a for mounting to the headboard 11a, and includes a worm pinion 36a enmeshed with a worm gear 51a in turn connected to the crank 28a by a threaded nut 66a arranged essentially similarly to the corresponding parts in the embodiment first above discussed. In the modified form, the shaft 74 is preferably of non-circular form such as rectangular cross section as illustrated in Figure 9, and is mounted through the hub 38a of gear 36a and through a stop nut 41a threaded into a bracket side 32a as in the first embodiment. Rotation of crank 28a in a clockwise direction as viewed in Figure 8 of the drawing will rotate the shaft 74 and its drums 76 and 77 in a direction reeling in the cables 13a with a corresponding raising of the mattress frame 14a. In this direction of rotation, the head 49a of nut 41a is backed away from the bracket side 32a. Upon rotation of the crank 28a in an opposite or counter-clockwise direction, the drums 76 and 77 will be rotated to pay out cable and permit a lowering of the frame 14a, and during such rotation the head 49a of nut 41a is advanced in the direction of the bracket side 32a, to provide a stop to further rotation in this direction when the frame has reached a desired lowermost position. After reaching this latter position, further clockwise rotation of the crank 28a will unthread nut 66a and effect a de-coupling of the crank drive connection as more fully described in connection with the first embodiment. Preferably, the opposite ends 78 and 79 of shaft 74 are extended through axial bores provided in the drums 76 and 77 and are formed with cylindrical end portions for journaling in bearings 81 and 82 mounted in the headboard. Preferably, the bores in the drums are broached to fit the non-circular cross section of the shaft to insure rotation of the drums with the shaft. At the same time, some longitudinal movement of the drums on the shafts is desirably permitted for level winding of the cable onto the drums.

The mechanism may be conveniently installed within the headboard by forming the latter of two half-sections as best illustrated in Figures 1, 2, 6 and 9 of the drawings, with appropriate

internal recesses, grooves and openings provided in the two half-sections to accommodate the mechanism as described and illustrated in the drawings. In such a construction, the worm shaft end 51 may be extended through the outer 5 of the headboard sections as illustrated in Figures 1, 6 and 9, for convenient attachment of the crank, and with the crank provides the only exposed part of the mechanism. As above noted, the crank may be easily detached where it is desired to position the headboard of the crib against a wall or the like or whenever it is desired to prevent operation of the mechanism by the occupant of the crib.

I claim:

1. A mechanism for raising and lowering a crib mattress frame comprising, rotary drive means adapted for connection to a crib mattress frame to effect on rotation of said means in one direction a raising of said frame and on rotation in an opposite direction a lowering of said frame, stop means limiting the rotation of said drive means in said last-mentioned direction to a desired lowermost position of said frame, manually operable means connected to said drive means to effect rotation thereof to said stop means, and means automatically effecting disconnection of said manual means from said drive means upon rotation of said drive means to said stop means.

2. A mechanism for raising and lowering a crib mattress frame comprising, gear means providing a rotary drive adapted for connection to a crib mattress frame to effect on rotation of said means in one direction a raising of said frame and on rotation in an opposite direction a lowering of said frame, stop means limiting the rotation of said gear means in said last-mentioned direction to a desired lowermost position of said frame, a manually operable crank means releasably connected to said gear means for effecting rotation thereof to said stop means, and means automatically effecting disconnection of said crank means from said gear means upon rotation of the latter to said stop means.

3. A mechanism for raising and lowering a crib mattress frame comprising, a cable drum journalled for rotation, cable connected to said drum for connection to a crib mattress frame to effect on rotation of said drum in one direction a raising of said frame and on rotation in an opposite direction a lowering of said frame, stop means limiting the rotation of said drum in said last mentioned direction to a desired lowermost position of said frame, gear means connected to said drum for effecting rotation thereof, a manually operable crank releasably connected to said gear means for effecting rotation thereof and said drum to said stop means, and means functioning to automatically disconnect said crank from said gear means upon rotation of said drum to said stop means.

4. A crib mattress frame raising and lowering mechanism comprising, a bracket adapted for mounting on the headboard of a crib, a drum journalled for rotation by said bracket, a cable carried by said drum for connection to said frame to effect a raising of said frame upon rotation of said drum in one direction and a lowering of said frame on rotation of said drum in an opposite direction, gear means carried by said bracket and connected to said drum for effecting rotation thereof, screw means carried for rotation with said drum and threadably connected to said bracket for limiting the rotation of said drum in

said last mentioned direction to a desired lowermost position of said frame, a crank releasably connected to said gear means for effecting rotation thereof, and means automatically breaking the drive connection of said crank and gear means upon rotation of said drum to its stop position aforesaid.

5. A crib mattress frame raising and lowering mechanism comprising, a bracket adapted for mounting on the headboard of a crib, a drum journalled for rotation by said bracket, a cable carried by said drum for connection to said frame to effect a raising of said frame upon rotation of said drum in one direction and a lowering of said frame on rotation of said drum in an opposite direction, threaded stop means carried for rotation with said drum and having a limited threaded connection to said bracket limiting the rotation of said drum in said last mentioned direction to a desired lowermost position of said frame, a spur gear connected to said drum for rotation therewith, a worm gear journalled for rotation by said bracket and enmeshed with said spur gear, and a crank connected to said worm gear for rotation thereof, said crank having a threaded connection to said worm gear arranged to lock upon rotation in said first-mentioned direction and to automatically unlock upon rotation in said second-mentioned direction when said stop position of said drum is reached.

6. A mechanism for raising and lowering a crib mattress frame comprising, rotary drive means adapted for connection to said frame to effect on rotation of said means in one direction a raising of said frame and on rotation in an opposite direction a lowering of said frame, stop means limiting the rotation of said drive means in said last-mentioned direction to a desired lowermost position of said frame, a crank having a threaded connection to said drive means for rotation thereof, said connection being arranged to tighten to a locked position on rotation of said crank to effect rotation of said drive means in said first direction and to loosen to a decoupled drive connection on rotation of said crank in an opposite direction after movement of said drive means is prevented by said stop means.

7. In a mattress frame raising and lowering mechanism, a bracket having spaced parallel sides, a spur gear formed with a hub journalled for rotation in one of said sides, a nut threaded into the other of said sides in axial alignment with said hub, said hub and nut having axially aligned bores, a shaft mounted in said bores and providing joint rotation of said gear and nut, a drum having an axial bore mounted on said shaft for rotation therewith, said drum and shaft being formed with aligned openings, a cable mounted through said openings and adapted for connection to said frame and for winding onto said drum whereby rotation of the latter in one direction will effect a raising of said frame and rotation in an opposite direction will effect a lowering of said frame, a worm gear mounted for rotation on said bracket and enmeshed with said spur gear, a crank having a threaded connection to said worm gear for rotation thereof and driving of said drum, said nut being formed with a shoulder engageable with the adjacent bracket side to limit the rotation of said drum in its second-mentioned direction corresponding to a desired lowermost position of said frame, the threaded connection of said crank to said worm gear being such as to lock the two together on rotation of said crank in a direction

corresponding to the first-mentioned direction of said drum and to decouple to a loose connection on rotation of said crank in an opposite direction after movement of said drum is prevented by said nut.

8. In a mattress frame raising and lowering mechanism, a bracket having spaced parallel sides, a spur gear formed with a hub journalled for rotation in one of said sides, a nut threaded into the other of said sides in axial alignment with said hub, said hub and nut having axially aligned bores, a shaft mounted in said bores and providing joint rotation of said gear and nut, a drum having an axial bore mounted on said shaft for rotation therewith and having an end recess housing said nut permitting axial movement of said nut in said recess, a cable carried by said drum for winding thereon and adapted for connection to said frame to effect a raising of said frame upon rotation of said drum in one direction and a lowering of said frame upon rotation of said drum in an opposite direction, said nut having a shoulder engageable with the adjacent bracket side to limit the rotation of said drum in one direction and the axial depth of said recess coating with said nut to limit the rotation of said drum in an opposite direction, a worm gear mounted for rotation on said bracket and enmeshed with said spur gear, and a crank connected to said worm gear for effecting rotation thereof.

9. A crib mattress frame raising and lowering mechanism comprising, a bracket adapted for

mounting on the headboard of a crib substantially centrally of the length thereof, an elongated drive shaft carried for rotation by said bracket and projecting from the opposite sides thereof with the opposite ends of said shaft disposed in overlying relation to the corner posts of said crib, a drum mounted on each of said shaft ends for rotation therewith, cables carried by said drums and adapted for connection to said frame 15 for effecting vertical displacement thereof upon rotation of said drums, gear means carried by said bracket and connected to said shaft for effecting its rotation, stop means limiting the rotation of said shaft in a frame lowering direction to a desired lowermost position of said frame, a crank having a detachable drive connection to said gear means, and means automatically effecting a decoupling of said drive connection between said crank and said gear means upon rotation of said crank to effect rotation of said shaft to said stop means.
